UNITED STATES PATENT OFFICE.

ALEXANDER DIOSSY, OF BROOKLYN, NEW YORK.

TOY DEVICE.

1,094,886.

Specification of Letters Patent. Patented Apr. 28, 1914.

Application filed October 6, 1913. Serial No. 793,564.

To all whom it may concern:

Be it known that I, ALEXANDER DIOSSY, a citizen of the United States, and residing at Brooklyn, in the county of Kings and 5 State of New York, have invented certain new and useful Improvements in Toy Devices, of which the following is a specification, such as will enable those skilled in the art to which it appertains to make and 10 use the same.

This invention relates to toy devices, and the object thereof is to provide an improved device of this class which is designed to entertain and amuse both young and old; 15 a further object being to provide a toy device made in the form of and to represent a fire-cracker and with these and other objects in view, the invention consists in a device of the class specified constructed and 20 operated as hereinafter described.

The invention is fully disclosed in the following specification of which the accompanying drawing forms a part, in which the separate parts of my improvement are designated by suitable reference characters in 25 each of the views, and in which:—

Figure 1 is a side view of my improved toy device; Fig. 2 a similar view but showing the parts in a different position; and, 30 Fig. 3 a central longitudinal section on the line 3—3 of Fig. 2.

In the practice of my invention, I provide a tube *a* made of sheet metal, card board, or any suitable material and one end 35 of which is closed and the other open, and the opposite sides of the tube *a* are provided with longitudinal slots *a*² which extend from a predetermined point *a*³ adjacent to the open end *a*⁴ of the tube about half 40 the length of said tube, as shown at *a*⁵, where they are provided with oppositely curved extensions *a*⁶ terminating in horizontal slot members *a*⁷. Within the tube *a* is placed a longitudinally movable plug *b* 45 with which are connected headed pins or screws *c* which pass through the slots *a*² and into said plug, and said plug forms a longitudinally movable plunger between which and the closed end of the tube is 50 placed a spiral spring *d*. Mounted centrally in the plug *b* is a rod or stick *e* having a conical cap piece *e*², and to which is secured a flag *f* adapted to be rolled up on the rod or stick *e*, and the conical cap 55 or head *e*² is provided with a piece of wicking *e*³ representing the fuse of an ordinary

firecracker. With this construction, the flag *f* may be wound up or rolled up on the stick or rod *e* and is so indicated in dotted lines at *f*² in Fig. 2, and said stick or rod 60 may be forced into the tube *a*, the pins or screws *c* moving in the slots *a*² until the plug *b* reaches the point shown in dotted lines in Fig. 3 at *b*², and in this operation the pins or screws *c* will pass through 65 the curved extensions *a*⁶ of the slots *a*² and into the horizontal parts *a*⁷ of said slots, and will hold the stick or rod *e* with the flag *f* wound thereon within the tube *a*, as 70 shown in Fig. 1, in which position of said parts the device resembles an ordinary fire-cracker. By pressing the thumb on one of the pins or screws *c*, or the thumb and one finger on both of said pins or screws, the stick or rod *e* and plug *b* may be turned 75 so that the spring *d* will force said stick and plug outwardly, as shown in Figs. 2 and 3, at which time the flag *f* will unfurl, or may be unfurled, as shown in Fig. 2, and this operation may be repeated whenever, 80 or as often as desired.

The device may be made of any desired dimensions and in this way, I provide a toy which will be particularly attractive to young people, especially on holidays such 85 as the Fourth of July and Christmas, and changes in and modifications of the construction described may be made, within the scope of the appended claims, without departing from the spirit of my invention or 90 sacrificing its advantages.

Having fully described my invention what I claim as new and desire to secure by Letters Patent is:—

1. A toy of the class described comprising a tube open at one end and closed at the other, said tube being provided in its opposite sides with longitudinal slots which extend from a predetermined point near the open end thereof longitudinally thereof, and 100 the end portions of which adjacent to the closed end of the tube are provided with oppositely curved extensions, a plunger plug movable longitudinally in said tube, a spiral spring placed between the closed 105 end of said tube and said plug, headed pins passing through said slots into said plug, a rod secured centrally in said plug, and a flag connected with said rod, said rod being provided at its outer end with a conical head.

2. A toy device made to represent a fire-

cracker and comprising a tube one end of which is closed, and the other end of which is open, said tube being provided in its opposite sides with longitudinal slots which extend from a predetermined point near the open end thereof longitudinally thereof, and the end portions of which, adjacent to the closed end of the tube, are provided with oppositely directed extensions, a plug moveable longitudinally in said tube, headed pins passing through the slots in the tube and into said plug, a spiral spring placed between the closed end of said tube and said

15
plug, a rod secured centrally in said plug and provided at its outer end with a conical head having an imitation fuse, and a flag connected with said rod adjacent to the conical head.

In testimony that I claim the foregoing as my invention I have signed my name in 20 presence of the subscribing witnesses this 4th day of October 1913.

ALEXANDER DIOSSY.
